WILLIAM HERRSCHAFT, OF NEW YORK, N. Y.

SIGN OR OPTICAL APPARATUS

Application filed July 13, 1927. Serial No. 205,486.

The invention relates to optics and reflectors, the specific application of the invention being a sign, though other uses and applications of the invention are not excluded. The object is to provide an apparatus of this character which is very simple and inexpensive to make and operate, yet which is very effective.

The invention provides and utilizes a reflector for collecting light rays from a source adjacent the reflector and projecting a beam in the desired direction, which reflector is constituted by inexpensive reflector sections of the cylindrical class to accomplish substantially the same result as a considerably more expensive reflector of the spherical class, a further advantage of my reflectors being that they can be comparatively shallow and still intercept and utilize a large proportion of the rays emanating from the source.

In the accompanying drawings forming part hereoff:

Fig. 1 is a plan view of a portion of a sign embodying the invention, the casing being in section;

Fig. 2 is a front elevation;

Fig. 3 is a front elevation, with the casing in section;

Fig. 4 is a substantially central horizontal section through one of the units; and

Fig. 5 is a section on the line 5—5 of Fig. 4.

The source of light and the light reflecting means of the sign are housed in a box or series of boxes 2, having frame holders 3 at the front, in which are inserted changeable slides 4 of opaque material having apertures or windows 5 forming the sign characters.

The box or boxes contain a series of lighting and reflecting units, each consisting of an electric bulb 6, two concave side reflector sections 7, and two concave rear reflector sections 8. The reflector sections are glass mirrors, silvered on their convex sides, where the silvering is protected by a suitable coating.

The reflectors are cylindrical, as distinguished from spherical or ordinary parabolic, mirrors. Cylindrical mirrors are comparatively inexpensive, and for the purpose of signs, as employed herein, they lend themselves to the rectangular form better than do spherical or

ordinary parabolic reflectors. Furthermore, reflectors constituted of a plurality of cylindrical sections according to the plan of this invention can be comparatively shallow from front to back, with consequent important economy of space, yet the sides of the reflector extend well forward so as to intercept and utilize a very large part of the rays emanating from the source.

The source 6 is placed adjacent or in front of the apex of the two rear reflectors 8, which stand upright and incline laterally and toward the rear. The reflectors 7, also standing erect, are outside the outer ends of the reflectors 8 and extend forwardly and beyond the light source. The curvature of the mirrors 7 extends in the horizontal sense, whereas the curvature of the mirrors 8 extends in the vertical sense, so that these sections can be said to have their curvatures at right angles to each other.

The light rays from the source fall upon the inner sides of the mirrors 7, which are properly positioned and of proper curvature to reflect them to the mirrors 8, by which, in turn, they are reflected forwardly in a substantially parallel beam through the sign screen. In this way a very brilliant and powerful projection of light is obtained, with very small consumption of electrical energy. Such a sign is very effective as a daylight sign, and can, of course, also be used at night.

Cylindrical mirrors, of circular or approximately circular curvature can be used with sufficiently good results, particularly in the smaller sizes, but naturally the greatest efficiency can be realized by special curvatures, which can be readily calculated or arrived at for a particular case, such as to cause the light to be projected in as nearly as possible a parallel beam. The mirrors 7 need not be as high as the mirrors 8, and, of course, the mirrors 7 are of shorter and the mirrors 8 of longer "radius" of curvature.

Mirrors of parabolic curvature may be used. Practically speaking, the mirrors 7 are such as to reflect the light rays in substantially or nearly parallel vertical planes, so that they do not diverge very greatly, if at all, in the horizontal sense though they do in

the vertical sense. Similarly, the mirrors 8 are also of such curvature as to rectify, or largely rectify, the divergence in the vertical sense and reflect the rays out in a parallel or nearly parallel beam. The distance between the mirrors 7 and 8 determines the difference in their "radii" of curvature, and their angular relation is such as to project the beam in the desired direction.

10 Each reflector is preferably duplex as shown, but this is not absolutely essential, though very desirable. With considerably less efficiency a reflector consisting of only one mirror 7 and one corresponding mirror 8 might be used with each light. Conversely, reflectors consisting of greater multiples symmetrically disposed may be employed.

15 In the sign herein shown, each reflector, including the light source, is carried by a pivoted support 9, capable of swinging on a vertical axis 10.

20 This provision enables the reflectors to be swung somewhat to one side or the other, thus dimming the sign, as may be desirable at night when the illumination might, otherwise, be too blinding. It also enables the beams of light to be directed at an inclination to the length of the sign in cases where it may not be possible to place the signs so that they 25 directly face the spaces from which it is desired that the signs shall be principally viewed.

25 This plan also makes it possible to cause the sign to dim and flash, or wax and wane, alternately. To this end the several supports 30 are shown connected by arms 11 and a reciprocatory bar 12 to a crank 13 driven by an electric motor 14 through a worm gear 15. Through the operation of a suitable mechanism of this kind the reflectors will be oscillated from side to side across the mid-position, which can be considered as corresponding to the condition of strongest lighting to persons viewing the sign directly in face. 35 This constitutes a very simple way of securing a dimming or fluctuating effect.

40 It will be understood that the precise nature of the sign screen in front of the reflectors is not essential. It may be constituted in various ways, and need not be stationary.

45 While the invention has special novelty and value as a sign, the principle is also applicable to reflectors for other purposes, various illuminating arrangements, projectors and searchlights.

50 In this invention a reflector is built up, as it were, of a plurality of cylindrical reflectors, in such relation to each other and to the light source as to produce substantially the same result as an ordinary spherical or parabolic reflector. This involves much less expense than a spherical or ordinary parabolic mirror, and there are other advantages. It will be understood that the term cylindrical reflector is used to distinguish from the class of

spherical mirrors, which class includes ordinary parabolic mirrors. The curvature of my mirrors need not be circular, and indeed for best results the curvature is specially plotted, which can be easily done, given the space in which to work and the distances. 70

I claim:

1. A sign comprising a screen exhibiting a character or characters, a source of light behind the screen, and a reflector comprising two cylindrical concave mirrors disposed adjacent said source in such relation that the light rays are reflected from one mirror to the other and from the second mirror are reflected forwardly through the screen, the two mirrors having their curvatures at right angles to each other. 75

2. The combination with a source of light, of a reflector comprising two cylindrical concave mirrors disposed adjacent said source in such relation that the light rays are reflected from one mirror to the other and from the second mirror are reflected forwardly, the two mirrors having their curvatures at right angles to each other. 80

3. A sign comprising a screen, a source of light behind the screen and a reflector comprising a number of cylindrical concave sections arranged with their curvatures at right angles and in such relation to each other and to the light source as to reflect the light rays, from one to another and eventually through the screen, producing substantially the result of a reflector of the spherical class. 95

4. The combination with a light source, of a reflector comprising two lateral cylindrical concave sections and two rear cylindrical concave sections, the lateral and rear sections having their curvatures at right angles to each other, and the sections being in such relation to each other and to the light source as to reflect the light rays from one to another and eventually in the direction desired, producing substantially the result of a reflector of the spherical class. 100

5. A sign having a screen, a light source and a reflector, said reflector comprising two cylindrical concave sections having their curvatures at right angles, the sections of the reflector being in such relation to each other and to the light source that the rays from the source are reflected from one section of the reflector to the other and from the latter are directed forward, and means whereby the reflector can be swung to change the brilliance 115 of the sign. 120

6. A sign having a screen, a light source and a reflector, said reflector comprising two cylindrical concave sections having their curvatures at right angles, and means for oscillating the reflector to cause the sign to wax and wane. 125

7. The combination with a source of light, of a reflector comprising at least four cylindrical concave sections, the sections two and 130

two having their curvatures at right angles and being disposed in such relation to each other and to the light source that the rays from the source are reflected from the sections of one pair to the sections of another pair and from the latter are thrown in the direction desired.

8. In combination with a source of light, a reflector means adjacent said source to collect and project the rays therefrom, said means comprising a number of cylindrical concave sections arranged with their curvatures at right angles and in such relation to each other and to the light source as to reflect the light rays from one to another and eventually in the direction desired, producing substantially the result of a reflector of the spherical class.
